(57) **CLAIM**

The ornamental design for a game rack, as shown and described.

DESCRIPTION

FIG. 1 is a front perspective view of a game rack, showing my new design in use;

FIG. 2 is a rear perspective view thereof;

FIG. 3 is a front elevation view thereof;

FIG. 4 is a right elevation view thereof, the left elevation view being a mirror image thereof;

FIG. 5 is a rear elevation view thereof;

FIG. 6 is a top plan view thereof; and,

FIG. 7 is a bottom plan view thereof.

The broken lines showing game pieces in FIG. 1 depicts environmental subject matter that forms no part of the claimed design.
